TIMER FOR FOOD MIXERS

Alvin W. Holstein, St. Louis, Mo., assignor to
 Knapp-Monarch Company, St. Louis, Mo., a
 corporation of Delaware

Application March 29, 1952, Serial No. 279,374

9 Claims. (Cl. 200—35)

1

This invention relates to a timer or time switch particularly adapted for electrically operated food mixers, although it can be used for timing other electrically operated appliances and the like.

One object of the invention is to provide a time switch mechanism including clockworks for the timing period which is mechanically connected with a switch operating member to cause the switch to open a circuit after a predetermined time that has been set on the timing mechanism as by rotation of a manually operated dial.

Another object is to provide a control knob or the like for simultaneously turning on the switch and setting the clock works for the timing period, the clock works then operating after the dial is released for the purpose of turning the switch off again at the end of the timing period.

Still another object is to provide a mechanical connection between the dial and the switch which permits the dial to be manually rotated backwards for closing the switch independent of the clockworks whereupon it remains closed until such time as the dial is again manipulated for manually opening the switch, thus providing a combined timer and manual "on" switch.

A further object is to provide a cam and a rocker connection between a timing shaft and a switch operating arm which, upon setting of the timer mechanism, effects a rocking motion of the rocker to turn the switch on with a lobe of the cam passing the rocker and camming it to the on position, after which the rocker rotates back to the original position as the timer mechanism rotates during the timing period and is in condition to drop off the lobe of the cam when it registers with the drop thereof at the end of the timing period.

Still a further object is to provide detent means for normally stopping the rotation of the dial at the end of a timing period, this means, however, being capable of permitting the dial to be rotated in the same direction as it is driven by the clockworks for turning the switch on through the medium of an element carried by the dial and cooperating with the switch for this purpose, the detent then holding the dial in the on position until the dial is manually rotated back to the "off" position.

With these and other objects in view, my invention consists in the construction, arrangement and combination of the various parts of my timer for food mixers, whereby the objects contemplated are attained, as hereinafter more fully set forth, pointed out in my claims and illustrated in the accompanying drawings, wherein:

2

Figure 1 is a partial side elevation of a food mixer to which my timer has been applied.

Figure 2 is an enlarged vertical sectional view on the line 2—2 of Figure 1 showing the timer mechanism.

Figure 3 is a sectional view on the line 3—3 of Figure 2 to show the switch mechanism.

Figure 4 is a vertical sectional view on the line 4—4 of Figure 2 showing the timer in the "off" position.

Figure 5 is a detail of the detent mechanism on the line 5—5 of Figure 4 when the timer is in the "off" position.

Figure 6 is a view similar to a portion of Figure 3 showing the switch in the closed circuit position as assumed during the timing period.

Figure 7 is a view similar to a portion of Figure 4 showing the position of the parts right after the timer has been started on the resetting operation.

Figure 8 is a detail of the detent mechanism on the line 8—8 of Figure 7.

Figure 9 is a view similar to Figure 7 showing in dotted lines the set position and in full lines the position of the parts when the timer is passing through the timing period.

Figure 10 is a view similar to Figure 9 showing the position of the parts adjacent the end of the timing period when the switch is about to be turned off.

Figure 11 is a detail of the detent mechanism on the line 1—1 of Figure 10.

Figure 12 is a view similar to Figure 7 showing the mechanism adjusted for the manual "on" position after having assumed the "off" position of Figure 4; and

Figure 13 is a detail of the detent mechanism on the line 13—13 of Figure 12.

On the accompanying drawings I have used the reference numeral 20 to indicate a supporting post for a food mixer motor housing 22. This general type of food mixer is shown in my copending applications, Serial Nos. 272,036 and 272,037, filed February 18, 1952. Beater shafts 24 are shown depending from the motor housing 22 and are for the purpose of driving food mixer and whipper elements as disclosed in the copending applications referred to. The present application has to do with a timer therefor that can be set to energize the motor of the food mixer for a predetermined period of time.

My timer includes a housing 39 and a timer shaft 26 on which is mounted a clockworks-driven element such as a gear 28. A pair of discs 30 and 33 are secured to the shaft 26 on opposite sides of the gear 28. A friction washer 32 is in-

terposed between the disc 33 and the gear 28 so that the mechanism just described constitutes a friction clutch between the clockworks-driven element 28 and the timer shaft 26.

A timer shaft spring 34 is provided which tends to rotate the timer shaft 26 in a counter-clockwise direction (as viewed in Figure 4). Clockworks are indicated generally at 36 and a pinion 38 is operatively connected with the works thereof and meshes with the gear 28. The clockworks 36 form no part of my present invention and are shown merely diagrammatically. A cam 40 is secured to the timer shaft 26 and this cam has a lobe, the periphery of which is indicated at 43. The cam lobe has a drop 42 and a rise 44.

A bracket 46 is provided for supporting the timer housing 39 and is secured by means of screws 48 to a flange 50 of the motor housing 22. A pivot 52 is carried by a boss 55 of the timer housing 27 on which a bell crank-shaped switch operating lever 54 is pivoted. A rocker 56 is in turn pivoted at 57 to the lever 54 and has an upper ear 58 and a lower ear 60 which are adapted to alternately engage the upper and lower edges of the horizontal portion of the lever 54 during the operation of the timer as will hereinafter appear. The upper ear 58 is also adapted to coact with the drop 42, the periphery 43 and the rise 44 of the cam 40.

My timer mechanism is adapted to actuate a switch for the mixer motor which consists of the following. A switch block 62 is mounted by means of screws 64 on a flange 66 of the bracket 46. The switch block carries a stop 68, a movable switch blade 70, a stationary switch blade 74, and a switch blade actuator 78. Contacts 72 and 76 are supported by the switch blades 70 and 74 respectively. A toggle spring 80 is interposed between the switch blade actuator 78 and the movable switch blade 70 to secure snap action of the switch. The switch is normally biased to the open position shown in Figure 3 and is adapted to be closed when the switch blade actuator 78 is moved upwardly from the position shown in this figure to the position shown in Figure 6.

Wires 71 and 73 are connected with the switch blades 70 and 74 respectively. A third wire 75 extends from the current supply and so does the wire 75. The mixer motor is shown at M in Figure 3 and is connected with the wires 71 and 73 so as to be in series with the switch contacts 72 and 76 for control thereby.

A roller 82 is carried by the upper end of the vertical arm of the switch operating lever 54 and is adapted to coact with the switch blade actuator 78 for closing the switch at predetermined times as will appear in the description of the operation of my timer. A control knob 84 is mounted on the timer shaft 26 and is operatively connected with the shaft by means of an arm 86 secured to the shaft and/or the cam 40 and extending into a socket 88 of the control knob 84. The control knob is provided with suitable indicia 90 and with graduations 92 to cooperate with a pointer 94 in the control of the timer switch as will be described later.

A detent 96 is mounted on the bracket 46, and the knob 84 is provided with a rear surface 97 next to the motor housing 22 from which there is a projection 98 which forms a shoulder 99. The center of the projection 98 is provided with a notch 100 and the shoulder and notch are adapted to coact with the detent 96 during various manipulations of the control knob 84. The

control knob also has a flange 95 to coact at times with the roller 82 as shown in Figure 12.

Practical operation

To use my timer for timing purposes, the control knob 84 is rotated clockwise from the "off" position shown in Figure 1 to any of the numbers 1 to 11 shown at 90 and indicating minutes of timing by means of the graduations 92 cooperating with the pointer 94. The switch is open as shown in Figure 3 when the knob 84 is in the Figure 1 position and the various other parts of the timer are at that time in the position shown in Figures 2, 4 and 5.

As the control knob 84 is rotated clockwise as indicated by the arrow a in Figures 7 and 8, the shoulder 99 will leave the detent 96 as shown in Figure 8 and during the first part of the rotation, the drop 42 of the cam 40 will rock the rocker 56 about its pivot 57 as shown by the arrow on the rocker to the position shown in Figure 7 and at the same time will act on the upper ear 58 in a camming manner to swing the switch operating lever 54 from the position of Figure 4 to the position of Figure 7. The roller 82 on the switch operating arm will at that time engage the switch blade actuator 78 to move it from the position of Figure 2 to the position of Figure 6 with the toggle spring 80 snapped over center and the contacts 72 and 76 engaged for energizing the motor M.

The operator may continue the rotation of the control knob 84, which will also rotate the cam 40 clockwise such as to the dotted position shown in Figure 9 corresponding to one of the indicia 90 on the dial or knob 84. Then when the knob 84 is released, the timer spring 34 will rotate the timer shaft 26 counter-clockwise as indicated by the arrow b in Figure 9 which tilts the rocker 56 during the first part of the movement as from the dotted line to the full-line position of the cam 40 in this figure.

Thereafter the cam will continue to rotate throughout the timing period and, upon reaching the position shown in Figure 10 (rotation still being counterclockwise as indicated by the arrows c in this figure and in Figure 11) be in such position relative to the upper ear 58 of the rocker 56 that the rocker is about ready to drop at 42 of the cam for terminating the timing period. It will be noted that the shoulder 99 in Figure 11 has approached the detent 96 and engages it soon after the ear 58 drops at 42 to the "off" position that is shown in Figure 4. Then with slight further rotation of the knob, its shoulder 99 engages the detent 96 as in Figure 4.

When it is desirable to manually turn the mixer motor on for continuous rotation until such time as it is manually turned off again, the knob 84 is rotated counterclockwise (instead of clockwise as for timing) to the position shown in Figure 12. The detent 96 will then be in the notch 100 as in Figure 13 to retain the knob in this position until it is again turned to the off position of Figure 4. The flange 95 in Figure 12 engages the roller 82 for turning the switch on independent of the cam 40.

Some changes may be made in the construction and arrangement of the parts of my timer for food mixers without departing from the real spirit and purpose of my invention, and it is my intention to cover by my claims any modified forms of structure or use of mechanical equiv-

alents which may be reasonably included within their scope.

I claim as my invention:

1. In a timer, a normally open switch, a timing shaft biased to rotate in one direction, clockworks for controlling the rotation thereof in said direction, a friction drive between said shaft and said clockworks, a knob for rotating said shaft manually in either direction, a cam on said timing shaft, a switch operating lever coacting with said cam for closing said switch when the knob is rotated in an opposite direction away from the initial position for time setting the timer, said cam when it returns to initial position permitting said switch to reopen due to the coaction of said cam with said lever, and means of cooperation between said knob and said switch when the knob is manually rotated in the first direction, said means effecting closure of said switch independent of said cam.

2. In a timer, a normally open switch, a timing shaft biased to rotate in one direction, clockworks for controlling the rotation thereof in said direction, a friction drive between said shaft and said clockworks, a knob for rotating said shaft manually in either direction, a cam on said timing shaft, a switch operating lever coacting with said cam for closing said switch when the knob is rotated in an opposite direction for time setting the timer, said cam when it returns permitting said switch to reopen due to the coaction of said cam with said lever, and means of cooperation between said shaft and said switch when the knob is further rotated in the first direction against the action of said detent, said last means effecting closure of said switch independent of said cam.

3. In a timer, a normally open switch, a timing shaft biased to rotate in one direction, stop means therefor in an initial position, clockworks for controlling the rotation thereof in said direction, a friction drive between said shaft and said clockworks, a knob for overcoming said friction drive and rotating said shaft manually in an opposite direction, a cam on said timing shaft, a switch operating lever coacting with said cam for closing said switch when the knob is rotated in said opposite direction away from said initial position for time setting the timer, said cam when it returns to said initial position permitting said switch to reopen due to the coaction of said cam with said lever.

4. In a timer, a normally open switch, a timing shaft biased to rotate in one direction, clockworks for controlling the rotation thereof in said direction, a friction drive between said shaft and said clockworks, a knob for rotating said shaft manually in an opposite direction, a cam on said timing shaft, a switch operating lever coacting with said cam for closing said switch when the knob is rotated in said opposite direction for time setting the timer, said cam when it returns permitting said switch to reopen due to the coaction of said cam with said lever.

5. In a timer, a normally open switch, a timing shaft biased to rotate in one direction, stop means therefor in an initial position, clockworks for controlling the rotation thereof in said direction, a friction drive between said shaft and said clockworks, a knob for overcoming said friction

drive and rotating said shaft manually in either direction, a cam on said timing shaft, a switch operating lever coacting with said cam for closing said switch when the knob is rotated in an opposite direction away from said initial position for time setting the timer, said cam when it returns to said initial position permitting said switch to reopen due to the coaction of said cam with said lever, and means of cooperation between said knob and said switch when the knob is rotated in the first direction, said means of cooperation overcoming said stop means and effecting closure of said switch independent of said cam.

6. In a timer, a normally open switch, a timing shaft biased to rotate in one direction, clockworks for controlling the rotation thereof in said direction, a friction drive between said shaft and said clockworks, a knob for rotating said shaft manually in either direction, a cam on said timing shaft having a lobe, a switch operating lever for coaction therewith, to reopen said switch as said timing shaft rotates in said one direction, and means of cooperation between said knob and said switch when the knob is further rotated in the first direction, said last means effecting closure of said switch independent of said cam.

7. In a timer, a normally open switch, a timing shaft biased to rotate in one direction, clockworks for controlling the rotation thereof in said direction, a friction drive between said shaft and said clockworks, a knob for rotating said shaft manually in either direction, a cam on said timing shaft having a lobe, a switch operating lever, said lever coacting with said cam for closing said switch when the knob is rotated in one direction for setting the timer, said cam, when it returns to the initial position permitting the switch to reopen, and means of cooperation between said knob and said switch when the knob is further rotated in the first direction, said last means effecting closure of said switch independent of said cam.

8. In a timer, a normally open switch, a timing shaft biased to rotate in one direction, clockworks for controlling the rotation thereof in said direction, a friction drive between said shaft and said clockworks, a knob for rotating said shaft manually, a cam on said timing shaft having a lobe, a switch operating lever, said lever coacting with said cam for closing said switch when the knob is rotated in one direction for setting the timer, said cam, when it returns to the initial position permitting the switch to reopen.

9. In a timer, a normally open switch, a timing shaft biased to rotate in one direction, clockworks for controlling the rotation thereof in said direction, a friction drive between said shaft and said clockworks, a knob for rotating said shaft manually, a cam on said timing shaft having a lobe, a switch operating lever, said cam when said knob is released, coacting with said lever to reopen said switch, said knob being further movable to close said switch and retain it closed independent of said cam.
